FIBEROPTIC ILLUMINATION ASSEMBLY FOR SURGEON'S HEADBAND

Jacobus Kloots, Sturbridge, and Rato Buhler, Brimfield,
Mass., assignors to Applied Fiberoptics Incorporated,
Southbridge, Mass.

Filed Feb. 2, 1973, Ser. No. 328,937

Term of patent 14 years

Int. Cl. D26—99

U.S. Cl. D48—20 H

FIG. 1 is a front elevational view of fiberoptic illumination assembly for surgeon's headband showing our new design;

FIG. 2 is a right side elevational view thereof;

FIG. 3 is a top plan view;

FIG. 4 is a rear elevational view; and

FIG. 5 is a bottom plan view thereof.

We claim:

The ornamental design for fiberoptic illumination assembly for surgeon's headband, as shown.
